(57) **CLAIM**

The ornamental design for a mobile device car mount with air vent clip, as shown and described.

DESCRIPTION

FIG. 1 is a top, perspective view of a mobile device car mount with air vent clip according to the design;

FIG. 2 is a bottom, perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate portions of the mobile device car mount with air vent clip, which form no part of the claimed design. The dash-dot broken lines immediately adjacent to the shaded areas represent boundaries of the claimed design and form no part thereof.
